UNITED STATES PATENT OFFICE.

WILLIAM H. WOODARD AND LANRIC D. BENEDICT, OF CLEVELAND, OHIO.

STOVE-RACK.

SPECIFICATION forming part of Letters Patent No. 255,068, dated March 14, 1882.

Application filed February 6, 1882. (No model.)

To all whom it may concern:

Be it known that we, WILLIAM H. WOODARD and LANRIC D. BENEDICT, of Cleveland, in the county of Cuyahoga, and in the State of Ohio, have invented certain new and useful Improvements in Stove and other Racks; and we do hereby declare that the following is a full, clear, and exact description thereof, reference being had to the accompanying drawings, and to the letters of reference marked thereon, making a part of this specification.

This invention relates to improvements on racks which are used in the ovens of stoves of various kinds, ice-chests, refrigerators, and in places generally where it is desired to support objects on racks and allow free ventilation.

The nature of our invention consists, first, in a rack which is composed of sheet-metal channeled bars united at their ends to other channeled bars, which receive the ends of the former bars and afford rigid attachments therefor; second, in novel fastenings for uniting the ends of the channeled bars, as will be herein-after explained.

In the annexed drawings, Figure 1 is a bottom view of one of the improved racks. Fig. 2 is a cross-section through the same. Fig. 3 is a bottom view of a rack having its longitudinal channeled bars secured to the end bars by lips formed on the longitudinal bars. Fig. 4 is a sectional view of the fastenings for the bars of Fig. 3. Figs. 5 and 6 are sectional details, showing modifications of the lipped fastenings.

The following description of our invention, in connection with the accompanying drawings, will enable others skilled in the art to understand it.

A A designate what we shall denominate the "longitudinal bars" of the rack, which are arranged parallel to each other, and which are rigidly secured to end bars, B B, thus forming a rectangular rack. The bars are all made of sheet-metal, bent so as to form channels of rectangular or acute-angular form when seen in cross-section. These channeled bars may be readily produced from narrow strips by machinery suitably adapted to the purpose. The

ends of the longitudinal bars A are inserted into the channels of the end bars, B, and rigidly secured thereto by rivets a. (Shown in Figs. 1 and 2.)

The rack of Figs. 3 and 4 is similarly formed to that represented by Figs. 1 and 2; but, instead of using rivets a, we cut short slits through the upper angles of the end bars, B B, and insert through the slits lips or tongues b, which are formed on the ends of the bars A. These lips are then turned up and pressed down over the angles of the end bars, B, forming rigid fastenings.

If desired, lips b b may be formed on each end of each bar A, passed through transverse slits made through the backs of the end bars, and firmly pressed against these bars, as shown in Fig. 5.

As a modification of the lipped fastenings, a long lip, b, (see Fig. 6,) may be compressed between the flanges of a bar, B, by firmly closing the flanges after the lip is inserted between them.

It will be seen from the above description that we have a wrought-metal rack formed of channeled bars A, secured by rivets or lipped fastenings to end bars, which are also channeled. Such a rack is much cheaper than wire racks, and easier made, and is not liable to break or crack, like the cast-metal racks.

We claim as our invention—

1. A rack for the purpose described, consisting of longitudinal and end bars formed of wrought metal, channeled and secured together, substantially as described.

2. The combination of lipped fastenings b with a rack composed of wrought-metal channeled bars, substantially as described.

In testimony whereof we affix our signatures, in presence of two witnesses, this 25th day of January, 1882.

WILLIAM H. WOODARD.
LANRIC D. BENEDICT.
